ATTORNEY.

UNITED STATES PATENT OFFICE.

OSWALD S. PULLIAM, OF PITTSBURG, PENNSYLVANIA.

METALLIC RAILWAY-TIE.

No. 813,668.

Specification of Letters Patent.

Patented Feb. 27, 1906.

Application filed September 28, 1905, Serial No. 279,805.

To all whom it may concern:

Be it known that I, OSWALD S. PULLIAM, a citizen of the United States, residing at Pittsburgh, in the county of Allegheny and State 5 of Pennsylvania, have invented new and useful Improvements in Metallic Railway-Ties, of which the following is a specification.

The object of my invention is to provide a new and improved metallic railway-tie; and 10 to this end the present invention consists of a metallic railway-tie, in the construction and in the combination of parts all as hereinafter described and claimed.

In the accompanying drawings, which 15 illustrate applications of my invention, Figure 1 is a perspective view of several ties constructed in accordance with my invention applied to two rails; Fig. 2, a broken view of a modified form of tie in side elevation; Fig. 3, a view similar to Fig. 2, showing a different arrangement of slots in the web; and Fig. 4, a detail vertical sectional view.

Referring to the drawings, A and B represent two rails of the usual form.

25 My invention comprises a beam having a top member 1, a bottom member 2, and a vertical web 3, and, as illustrated and as preferred, the tie is constructed of a rolled or cast structural beam in the form of an I- 30 beam. In the forms of ties shown by the drawings I employ two sets of engaging lugs 4, which are adapted to be bent over to engage the rail-bases. These lugs, as shown, are formed integral with the top member 1; but I do not desire to be limited to this mode 35 of securing the rails to the ties. Formed integral with and extending outwardly from opposite faces of the web 3 are two projections 5. The purpose of these projections, 40 which in practice are embedded in the track-ballast, is to prevent the lateral movement of the ties.

The vertical web 3 is formed at each end 45 in the form of Fig. 1 with a slot 6 and in the form of Fig. 2 with a plurality of similar slots. These slots extend inwardly from the ends of the tie for a sufficient distance to give the required amount of spring to the ties as the load is passing over.

50 What I claim is—

1. A metallic railway-tie comprising a cast structural beam having a vertical web and top and bottom members, and means for giving

ing elasticity to the tie comprising a slot formed in the web, substantially as set forth. 55

2. A metallic railway-tie comprising a beam having a vertical web and means for giving elasticity to the tie comprising top and bottom members, and a horizontally-disposed slot formed in the web, substantially 60 as set forth.

3. A metallic railway-tie comprising a rolled structural beam having a vertical web and top and bottom members, and means for giving elasticity to the tie comprising a slot 65 formed in the web at each end of the beam, substantially as set forth.

4. A metallic railway-tie comprising a beam having a vertical web and top and bottom members, and means for giving elasticity 70 to the tie comprising a plurality of slots formed in the web, substantially as set forth.

5. A metallic railway-tie comprising a rolled structural I-beam having means for giving elasticity to the tie comprising a horizontally-disposed slot formed in the web 75 thereof, substantially as set forth.

6. A metallic railway-tie comprising a rolled structural I-beam having means for giving elasticity to the tie comprising a horizontally-disposed slot formed in the web at 80 each end of the beam, substantially as set forth.

7. A metallic railway-tie comprising a rolled structural I-beam having means for giving elasticity to the tie comprising a plurality of horizontally-disposed slots formed 85 in the web of the beam, substantially as set forth.

8. A metallic railway-tie comprising a beam having a vertical web and top and bottom members, means for giving elasticity to the tie comprising horizontally-disposed slots formed in the web, and outwardly-extending 90 projections formed integral with the web, 95 substantially as set forth.

9. A metallic railway-tie comprising a beam having a vertical web and top and bottom members, engaging lugs formed integral with the top member, means for giving elasticity to the tie comprising horizontally-disposed slots formed in the web, and outwardly-extending 100 projections formed integral with the web, substantially as set forth.

10. A metallic railway-tie comprising an I-beam having horizontally-disposed slots 105

5 formed in its web for giving elasticity to the tie, engaging lugs formed integral with its top member, and outwardly-extending projections formed integral with the web, substantially as set forth.

11. A metallic railway-tie comprising an I-beam having a horizontally-disposed slot formed in its web at each end of the beam for giving elasticity to the tie, engaging lugs

formed integral with its top member, and outwardly-extending projections formed integral with the web, substantially as set forth.

In testimony whereof I affix my signature in presence of two subscribing witnesses.

OSWALD S. PULLIAM.
